CLAIM

The ornamental design for a karaoke device, as shown and described.

DESCRIPTION

FIG. 1 is a top perspective view of a karaoke device showing my new design;

FIG. 2 is a top perspective view thereof in a different configuration;

FIG. 3 is a rear elevational view thereof;

FIG. 4 is a right side elevational view thereof;

FIG. 5 is a front elevational view thereof;

FIG. 6 is a left side elevational view thereof;

FIG. 7 is a bottom plan view thereof; and,

FIG. 8 is a top plan view thereof.

The broken lines show portions of the karaoke device which form no part of the claimed design.
